UNITED STATES PATENT OFFICE

2,348,739

GASEOUS DISCHARGE LAMP CIRCUIT

George B. Horn, Fairfield, Conn., assignor, by
mesne assignments, to The Wheeler Insulated
Wire Company, Incorporated, Bridgeport,
Conn., a corporation of Delaware

Application September 18, 1941, Serial No. 411,279

9 Claims. (Cl. 315—96)

This invention relates to electric gaseous discharge lamps or fluorescent tube circuits having a plurality of lamps or tubes therein, and is an improvement over the device disclosed and claimed in my Patent No. 2,241,261.

In that patent there is disclosed an arrangement using an autotransformer for operating a plurality of fluorescent tubes which is satisfactory for many installations. However, it has been found that under certain conditions the temperature rise in the transformer becomes too great and the current requirements for operating the tubes too high. It has also been found that the wave form in the leading or capacitive tube deviated substantially from a sine wave.

These difficulties have been overcome by the present invention by inserting a single choke in the primary circuit in series with and between the common point of connection and the alternating supply therefor.

When the circuit is so arranged, the starting current in both the leading and lagging tubes is reduced to substantially the minimums as set up by the Electrical Testing Laboratories, Inc., the running current of the leading tube is reduced, the temperature rise of the transformer is greatly reduced, and the wave form of the current in the leading tube is changed to substantially a sine wave without in any way affecting the wave form of the lagging tube which is practically a sine wave.

The value of the impedance of the choke so inserted in the circuit is small and, within a reasonable range, not critical as the position of the coils on the transformer may be shifted to compensate for such variations in the value of the choke, together with suitable changes in the condenser in the circuit.

Other features and advantages of the invention will be apparent from the specification and claims when considered in connection with the drawing, in which:

Figure 1 shows a diagram of the fluorescent tube circuit of the present invention.

Figure 2 shows a comparison of the wave forms of the current in the leading tube as produced in an oscillograph.

In the illustrated form of the invention, the circuit includes two electric gaseous discharge lamps or fluorescent tubes 10 and 11 having filaments 10a, 10b, and 11a and 11b, at opposite ends thereof.

The filaments are connected in series by means of starter switches diagrammatically shown at 10c and 11c. These switches preferably are of the

type which automatically close the filament circuit to heat the filaments to activate the tubes and upon opening cause the tubes to arc over. Each switch remains in open circuit condition as long as there is an electron flow through the tube between the filaments.

Power for operating the tubes is supplied by a transformer 12 having an elongate core 13, a primary winding 14 and a pair of secondary 10 windings 15 and 16. The windings 14, 15 and 16 are shown as being connected to form an autotransformer with the secondary winding 15 connected to energize the filaments of tube 10 and the secondary winding 16 connected to the filament circuit of tube 11 to energize them. A condenser 17 is included in one of the tube circuits.

The currents for the two tubes are thus electrically displaced so that one is leading current 20 and the other lagging. Herein the tubes are referred to as leading or capacitive tubes and lagging or inductive tubes.

The circuit thus far described is the same as described in my patent noted above and is highly satisfactory under normal conditions. However, it has been found, under certain conditions, that the temperature rise in the transformer is too great and that the operating currents are too high.

30 I have discovered that these difficulties are overcome by inserting a choke coil 18 in series with, and between, the common terminal of the primary and its connection to a source of alternating current indicated at 19.

35 The impedance of the choke is relatively low and its value, within reasonable limits, is not critical as the position of the transformer windings can be adjusted on the core and the value of the condenser 17 varied to compensate for slight variations thereof.

40 The improved results obtained with this new circuit can best be shown by a comparative test of it with a circuit omitting the choke. For example, in a test conducted on a circuit having 45 40 watts output at the tubes, it was found that a 12 to 15% decrease in temperature rise was obtained when the choke is included in the circuit. When devices of this type are used in places where ventilation and cooling conditions are bad, this is a substantial advantage.

With regard to the current requirements of the tubes, the running current in the lagging tube of the circuit without the choke, which we shall call the former circuit, was .40 amp., and with the present circuit was also .40 amp., in-

dicating that by putting the choke in the circuit there was no change in the value of the running circuit for the lagging tube. However, the current in the leading tube in the former circuit was .44 amp., whereas with the new circuit it was only .40 amp. Thus it will be seen a substantial drop in the normal running current in the leading tube circuit is produced in the present arrangement.

The starting current for the tubes is greatly affected by the inclusion of the choke in the circuit. The Electrical Testing Laboratories, Inc., has established the minimum and maximum starting currents which are acceptable to tube manufacturers. These limits are minimum .55 amp. and maximum .75 amp. With the former circuit, the starting current was .70 amp. in the lagging tube and .65 amp. in the leading tube. It will be noted that although within the limits specified by the Electrical Testing Laboratories, Inc., these values are closer to the upper limits.

With the new circuit, however, the starting current in the lagging tube is reduced to .58 amp. and in the leading tube to .56 amp., which values are approximately the minimum specified values.

This reduction of the starting current is particularly valuable in the case where the starter circuit contacts stick and fail to open the circuit and also when the tubes become deactivated, that is, where there is no electron flow between the filaments at the opposite ends of the tube. When this occurs, the starting circuit automatically attempts to bring the filaments to that temperature at which the tube will become activated, and, since the tube will not arc over, a periodic closing and opening of the starting switch will take place with the attendant flow of starting current.

With the new circuit, the current demand is substantially reduced and naturally the temperature of the unit is reduced.

The wave forms of the currents in the two circuits were examined by means of an oscillograph. The current in the lagging tube was found to be substantially a sine wave and was not visibly affected by the inclusion of the choke in the primary circuit. The current in the leading tube, however, in the former circuit was not a sine wave, but had a shape as shown in Fig. 2 by the dot and dash line 20. It will be noted that it is generally peaked and has a relatively high maximum value. With the choke in the primary circuit, however, the wave form of the current in the leading tube took the form shown by the solid line 21 in Fig. 2, which, it will be noted, was substantially a sine wave. This new wave form was substantially the wave form of the current in the lagging tube. The wave forms in Fig. 2 were traced from an actual comparison test on the oscillograph.

This change in wave form is important from an operating standpoint as the leading tube no longer has a high or peak value but is substantially the same as that of the lagging tube.

The foregoing comparison has been made by way of example only and is not intended to limit the scope of the invention.

While the circuit of the transformer is illustrated as that of an autotransformer of the type disclosed and claimed in my patent, the present invention is not to be limited to a circuit employing only this transformer, but may be used with other transformer connections so long as a choke or the like is included in the primary

circuit which affects the secondary supplying the leading tube.

Variations and modifications may be made within the scope of this invention and portions of the improvements may be used without others.

I claim:

1. In a circuit for energizing a pair of electric gaseous discharge lamps, means for producing electrically displaced energizing currents, a leading current for one lamp and a lagging current for the other lamp; a transformer having a primary coil and a pair of secondary coils, all of said coils having a common terminal, one secondary coil being connected to each lamp; and a choke coil in a supply line connected to the common terminal of the transformer, said choke reducing the operating current requirements for said tubes.

2. A fluorescent tube circuit having a leading tube and a lagging tube therein; a source of alternating current; an autotransformer connected to said source and having a primary coil and a pair of secondary coils, one of the secondary coils being connected to the leading tube and the other secondary coil being connected to the lagging tube to operate said tubes, said primary and secondary coils having a common terminal; and a choke coil connected in series between the common terminal of the primary of the transformer and the source of alternating current, said choke coil reducing the starting and running current required to operate said leading and lagging tube.

3. A fluorescent tube circuit having a leading tube and a lagging tube therein; a source of alternating current; an autotransformer connected to said source and having a primary coil and a pair of secondary coils, one of the secondary coils being connected to the leading tube and the other being connected to the lagging tube to operate said tubes; and means for reducing the temperature rise in the transformer for a given watt output including a choke coil connected in series with and between the common terminal of the transformer and the source of alternating current.

4. A fluorescent tube circuit having a leading tube and a lagging tube therein; a source of alternating current; an autotransformer connected to said source and having a primary coil and a pair of secondary coils, one secondary coil being connected to the leading tube and the other being connected to the lagging tube to operate said tubes, all of said coils having a common terminal; and means for producing substantially a sine wave in the current in the leading tube comprising a choke coil connected to the common terminal and in series with the source of alternating current.

5. A fluorescent tube circuit having a leading tube and a lagging tube therein; means for supplying alternating current; an autotransformer connected to said means and having a primary coil and a pair of secondary coils, one secondary coil being connected to the leading tube and the other connected to the lagging tube to operate said tubes, all of said coils having a common terminal; and means connected to the primary coil of the autotransformer for varying the wave form of the leading tube without affecting the wave form of the lagging tube, said means including a choke coil connected in series between the common terminal and the supply means.

6. A fluorescent tube circuit having a leading tube and a lagging tube therein; a source of alternating current; an autotransformer connected to said source and having a primary coil and a pair of secondary coils, one secondary coil being connected to the leading tube and the other being

connected to the lagging tube to operate said tubes, all of said coils having a common terminal; and means for reducing the operating current in the tubes for a given watt output at the tubes comprising a choke connected between said common terminal of the transformer and the source of alternating current.

7. A fluorescent tube circuit having a leading tube and a lagging tube therein; a source of alternating current; an autotransformer connected to said source and having a primary coil and a pair of secondary coils, one secondary coil being connected to the leading tube and the other being connected to the lagging tube to operate said tubes, all of said coils having a common terminal; and means for reducing the starting current in both the leading and lagging tubes for a given watt output at the tubes comprising a choke connected in series between the common terminal of the transformer and the source of alternating current.

8. A fluorescent tube circuit having a leading tube and a lagging tube therein; a source of al-

ternating current; an autotransformer connected to said source and having a primary coil and a pair of secondary coils, one secondary coil being connected to the leading tube and the other connected to the lagging tube to operate said tubes, all of the coils having a common terminal; and means for reducing the running current in the leading tube for a given watt output at the tubes comprising a choke connected in series with the common terminal of the transformer.

9. A fluorescent tube circuit having a leading tube and a lagging tube therein; a supply of alternating current; an autotransformer having a core, a pair of secondary coils on the core and a primary coil connected to said source of alternating current, one of the secondary coils being connected to the leading tube and the other connected to the lagging tube, all of said coils having a common terminal; and means including a choke connected in the supply line to the common terminal for reducing the current requirements of each tube for a given watt output at the tubes.

GEORGE B. HORN.
